Primary Examiner — Garth Rademaker*Assistant Examiner* — Melanie Pellegrini(74) *Attorney, Agent, or Firm* — Kevin Keener; Keener and Associates P.C.(57) **CLAIM**

The ornamental design for a chain earring, as shown and described.

DESCRIPTION

FIG. 1 is a top perspective view of a chain earring; FIG. 2 is an enlarged sectional view of a link of the chain earring shown separately for completeness of illustration; FIG. 3 is a front elevational view thereof; and, FIG. 4 is a side elevational view thereof. The broken lines shown in the drawings illustrate portions of the chain earring that form no part of the claimed design.
